CLAIM

The ornamental design for a remote controller for air conditioner as shown and described.

DESCRIPTION

FIG. 1 is a perspective view of a remote controller for air conditioner showing my new design;

FIG. 2 is a front view thereof;

FIG. 3 is a rear view thereof;

FIG. 4 is a right side view thereof; a left side view being a mirror image;

FIG. 5 is a top view thereof; and,

FIG. 6 is a bottom view thereof.

The broken lines in the drawings illustrate portions of the remote controller for air conditioner which form no part of the claimed design.

1 Claim, 5 Drawing Sheets
